LEWIS J. GREENAWALT, OF MANSFIELD, OHIO, ASSIGNOR TO WESTINGHOUSE ELECTRIC & MANUFACTURING COMPANY, A CORPORATION OF PENNSYLVANIA.

THERMOSTATIC DISK.

Application filed February 1, 1927. Serial No. 165,105.

My invention relates to thermostatic devices and particularly to bimetallic disks therefor.

An object of my invention is to provide a thermo-responsive bimetallic disk so constructed that it may be actuated from an initially curved position to a position of reverse curvature without subjecting the disk to severe internal stresses.

10 In practicing my invention, I provide a bimetallic disk having a spherically or non-developable curved surface the curvature of which is reversed by subjecting the disk to a temperature of a predetermined value.

15 In order to reduce the stresses in the disk incident to reversing its curvature, a plurality of sections are removed from the disk whereby portions are provided that extend radially from a peripheral portion towards 20 the center thereof. These portions are separated from each other at the center of the disk in order that the respective ends thereof may move independently of each other.

25 In the single sheet of drawings, Fig. 1 is a top plan view of a thermostatic switch embodying my invention;

Fig. 2 is a view in side elevation, partly in section of the device illustrated in Fig. 1; and

30 Fig. 3 is a top plan view of a bimetallic disk embodied in the device illustrated in Figs. 1 and 2.

In the drawings, a thermostatic switch 11 comprises a base 12, a disk of insulating material 13 disposed between the base 12 and a plurality of stationary contact plates 14, 15, 16 and 17, of arcuate shape, and a bimetallic disk 18 that is attached to the base 12 by means of a screw-threaded stud 19.

40 The stationary contact members 14 and 15 are secured to the base 12 by means of terminal bolts 21 and 22, the heads of which are peened over against the contact members. The contact members 16 and 17 are suitably secured to the base 12 by such means as rivets 23, the heads of which may be peened or spun over against the contact members and the base 12. The terminal bolts 21 and 22 and the rivets 23 are suitably insulated from 50 the base 12.

The bimetallic disk 18 is of the type, disclosed and claimed in the Patent #1,448,240 issued to J. A. Spencer, having a spherically curved or non-developable portion so that it 55 may be actuated from one position to another

with a snap motion by a reversal of its curvature. The reversal of curvature of the spherically curved portion of the disk is caused by the unequal expansion of the metals of which it is composed.

60 A plurality of portions of the disk 18 are so cut away (see Figs. 1 and 3) that a plurality of radial portions or spokes 24 are provided which extend from an annular rim portion 25 towards the center of the disk. 65 The portions 24 are severed at the ends terminating at the center of the disk in order to permit free movement thereof. The inner ends of the portion 24 are arcuate in shape in order that the disk 18 may be mounted on 70 the stud 19 and be operatively secured thereto by such means as a nut 26. A suitable clearance is provided between the nut 26 and a shoulder portion (not shown) on the stud 19 whereby the ends of portion 24 may move 75 longitudinally along the stud 19.

70 A plurality of movable contact members 26a are secured to the periphery or the rim portion of the disk 18 by means of washers 27 and pins 28. The ends of the pins 28 are spun over against the washers 27 and the contact members 26a in order to maintain the contact members in operative relation to the disk 18. Washers 29 of electric-insulating material are disposed between the disk 18 and the washers 27, thereby insulating the pins 28 and the contact members 26 carried thereby from the disk 18.

80 The contact-bridging members 26 are so spaced along the rim portion of the disk that they engage the adjacent ends of the contact members 14, 15, 16 and 17, thus providing a current-conducting path between the terminal bolts 21 and 22. A turning movement of the disk 18 on the stud 19 is 85 prevented by a pin 31 secured in the base 12 and extending through the disk 18 near the periphery thereof.

90 When the disk 18 is heated to a predetermined temperature, its curvature is suddenly reversed, thus causing the contact members 26 to be moved out of engagement with the stationary contact members 14, 15, 16 and 17 with a snap motion. The current-conducting path between the terminals 21 and 22 is, therefore, interrupted.

100 The stresses resulting from reversing the curvature of the disk, as illustrated in Fig. 2 of the drawings, is materially reduced by reason of the fact that the spokes or por-

tions 24 (see Fig. 3) may yield or deflect during the reversal of curvature of the rim portion of the disk. The strains in the disk are materially reduced also because the body 5 of metal, of which resistance to bending must be overcome in order to reverse the curvature of the disk is greatly diminished.

While I have made no mathematical analysis of the reduction in stresses obtained 10 by removing portions of the disk 18, as illustrated in the drawings, I have found by experiment that a disk constructed in this manner will operate an indefinite number of times and still maintain its resiliency. The 15 fact that the disk still maintains its resiliency after a large number of reversals of curvature is evidence that the strains are greatly reduced.

Various modifications may be made in the 20 device embodying my invention without departing from the spirit and scope thereof. I desire, therefore, that only such limitations shall be placed thereon as are imposed by the prior art and the appended claims.

25 I claim as my invention:

1. A thermo-responsive means for actuating the contact members of an electric switch with a snap motion, said means comprising a bimetallic disk having a spherically curved 30 surface, said disk being perforated to pro-

vide a plurality of spokes, the ends of which are free to move at the central portion of the disk.

2. A thermostatic disk comprising a bimetallic member having an outer portion 35 and a plurality of spaced portions extending radially towards the center of the disk, said spaced portions being disconnected at their inner ends.

3. A bimetallic disk having an initial 40 deformation therein for establishing two opposed limiting positions to which it may be actuated with a snap motion when predetermined different temperatures obtain therein, said disk comprising a bimetallic member having an annular portion and a plurality of portions projecting radially inwardly therefrom, said plurality of portions being disconnected at their ends.

4. A thermostatic device comprising a bimetallic disk having spaced portions cut away between the periphery and the center thereof, the portions remaining between the spaced portions being severed from each other at the center of the disk. 50

In testimony whereof, I have hereunto subscribed my name this 25 day of January, 1927.

LEWIS J. GREENAWALT.
